UNITED STATES PATENT OFFICE.

CHARLES FAWCETT BENNION, OF LEICESTER, ENGLAND, ASSIGNOR, BY MESNE ASSIGNMENTS, TO UNITED SHOE MACHINERY CORPORATION, OF PATERSON, NEW JERSEY, A CORPORATION OF NEW JERSEY.

GRIPPER.

1,305,435.

Specification of Letters Patent.

Patented June 3, 1919.

Application filed October 4, 1915. Serial No. 53,968.

To all whom it may concern:

Be it known that I, CHARLES F. BENNION, a subject of the King of England, residing at Leicester, Leicestershire, England, have 5 invented certain Improvements in Grippers, of which the following description, in connection with the accompanying drawings, is a specification, like reference characters on the drawings indicating like parts in the several figures.

This invention relates to grippers such for example, as are used in pulling-over machines of the type shown and described in U. S. Letters Patent No. 1,029,387, granted 15 on application of R. F. McFeeley. In this type of machine as usually constructed each gripper comprises a rigid jaw and a coöperative jaw pivoted relatively to the rigid jaw and arranged to swing toward the latter 20 through different angles. Since the planes of the gripping faces of the different jaws lie, therefore, at various angles to each other according to the thickness of the upper being seized, portions only of the gripping faces 25 of the jaws are efficiently utilized in actually holding the upper, with the result that under some conditions when the upper is tensioned about the last it tends to slip from between the jaws and is liable to become torn or 30 damaged.

Objects of this invention are to provide a construction of gripper in which the difficulties above referred to shall be obviated, and in general to improve the construction of grippers in respect to the effectiveness of their engagement with the material. To this and other ends, the invention provides a novel construction and arrangement of gripper jaws including provision 40 for relative adjusting movement of the gripping portions of the jaws in response to engagement with the material. In the construction herein shown, one of the gripper jaws is provided with a recess the bottom wall of which is curved about an axis 45 extending laterally of the gripper, and mounted in said recess is a gripping member which is adjustable in response to engagement with the material about the axis of the curve of said wall. With this construction the material is gripped effectively 50 by the coöperating gripping faces of the

jaws irrespective of the extent to which the jaws are permitted to close by the thickness of the material.

Another feature of the invention consists in a novel construction of gripper whereby the bite of the gripper upon the material is increased by the pull of the gripper. In the construction shown, wherein one of the gripper jaws carries a gripping member movable angularly relatively to the other jaw independently of the relative opening or closing movements of the jaws, such gripping member is so mounted as to cause it to be forced toward the opposite jaw in response to the relative pull between the gripper and the material. In the particular construction shown the gripping member is seated in a recess in the gripper jaw the bottom wall of which is curved about an axis which lies at the side of said member on which the gripping face of the member is located, and by reason of this construction the pull upon the material tends to swing the gripping member bodily lengthwise of the gripper jaw in such manner as to cause its outer edge portion to be forced toward the opposite jaw to bite the material with increasing pressure.

Still another feature of the invention, as embodied in a construction in which one of the gripper jaws comprises a gripping member angularly adjustable relatively to the other jaw, resides in novel yielding means for determining the normal position of the gripping member while permitting it to assume different positions in response to engagement with the material.

Other objects and features of the present invention will be more fully explained in the following description and then pointed out in the claims.

In the drawings:

Figure 1 is a side elevation, with parts in longitudinal section of a gripper embodying the present invention.

Fig. 2 is a front elevation of the movable jaw.

Fig. 3 is a side elevation, with parts in longitudinal section, showing the positions of the several parts when the gripper is holding stock under tension.

The gripper supporting and controlling

mechanism is preferably substantially the same as that disclosed in the above-mentioned patent and includes a casing or carrier 2 which supports the two jaws and contains the devices for operating them to grip and pull the stock. The jaw 3 is rigidly secured to the casing by a bolt 5 while the jaw 6 is pivoted on the pin 8 and has a tail piece 9 that is engaged by a roll 12 on a slide 13 for rocking the pivotal jaw 6 toward the coöperating jaw 3. The slide 13 projects upwardly through the casing and is connected with mechanism (not shown) by which the slide is operated for closing and raising the jaws.

As the jaw 6 swings about the pivot 8 toward the coöperating stationary jaw 3 the gripping face thereof, in constructions such as provided heretofore, assumes different angles relatively to the gripping face of the other jaw and differences in the thickness of different stock seized by the jaws causes corresponding variations in the angular relation of the gripping faces with the result that only a portion of the gripping faces of the jaws may be utilized for engaging the stock or may act with maximum efficiency, the upper portion of the gripping faces being relatively inefficient in seizing thin stock and the lower portion of the gripping faces being less than normally efficient in seizing thick stock.

In the illustrative embodiment of this invention the inside face of the pivoted jaw 6 is provided with a concaved recess 15 the bottom wall of which is curved lengthwise of the gripper about an axis substantially parallel to the pivotal axis of the jaw 6, and a gripper plate 16, the outer face of which is roughened to correspond with the gripping face of the rigid jaw, is loosely retained in this recess 15 by a spring plate 19. This spring plate is secured at one end to the jaw 6 by a screw 22 and has its opposite end bearing in a recess 23 in the toothed face of the gripper plate 16 against the gripper plate, thus retaining the plate in the recess while permitting sliding movement of the plate longitudinally of the jaw and also returning the plate to a normal position when the jaws are opened. The gripper plate 16 thus seats upon the bottom wall of the recess 15 as a bearing; the axis of the curve of this wall lying at the side of the plate 16 on which the gripping face of the plate is located. Flanges 25 on either side of the jaw 6 prevent movement of the sliding plate transversely of the jaw. It will be seen that with this construction whatever thickness of stock is being seized by the jaws the gripping plate of the pivoted jaw may adjust itself by a bodily swinging movement longitudinally of the jaw into parallelism with the coöperating gripping

face of the rigid jaw, thereby equalizing the gripping force between different parts of the gripping faces of the jaws and utilizing the entire gripping surfaces of the jaws for securely holding the upper while it is being drafted about the last. After the jaws have seized the upper material and are actuated to tension the upper about the last the downward strain tending to pull the upper material out of the jaws acts upon the gripping plate 16 with a tendency to move it lengthwise of the jaws, whereby its outer edge portion is forced by the curvature of the recess toward the gripping face of the stationary jaw and thus bites the upper material with increasing force independently of the mechanism for closing the jaws upon the upper material.

Although the invention is shown and described herein with reference to a gripper particularly designed for use in a pulling-over machine, it will be understood that the invention is not thus limited in its applicability but that the novel features are of general utility in grippers adapted for various kinds of work.

Having described a preferred embodiment of the invention, I claim as new and desire to secure by Letters Patent of the United States:

1. In a pulling-over machine gripper, the combination with a rigid jaw, of a jaw pivoted relatively to the rigid jaw to swing toward the latter through different angles for gripping upper materials of different thicknesses, said pivoted jaw having in its inner face a recess the bottom wall of which is concavely curved about an axis substantially parallel to the axis of said pivoted jaw, a gripping plate mounted in said recess and movable therein about the axis of said curve into parallelism with the gripping face of the other jaw, and a spring arranged to retain the gripping plate in said recess and to return it to a normal position when the jaws are opened.

2. In a gripper, the combination with a rigid jaw, of a jaw pivoted relatively to the rigid jaw to swing toward the latter through different angles for gripping stocks of different thicknesses, said pivoted jaw having in its inner face a recess the bottom wall of which is concavely curved longitudinally of the jaw, a gripping plate mounted in said recess and movable therein about the axis of said curve into parallelism with the gripping face of the other jaw, and a spring plate having one end fitting into a recess in the gripping plate for retaining said plate in the recess in said jaw and permitting the required movement of said plate longitudinally of the jaw.

3. In a gripper, the combination with a rigid jaw, of a jaw pivoted relatively to the

rigid jaw to swing toward the latter through different angles for gripping stocks of different thicknesses, one of the jaws having in its inner face a recess the bottom wall of 5 which is curved longitudinally of said jaw, and a gripping plate located in said recess and arranged for bodily positioning movement longitudinally of the jaws by the gripping force to present its gripping face in 10 parallelism with the gripping face of the co-operating jaw in the different angular positions of the swinging jaw assumed in gripping stocks of different thicknesses.

4. In a gripper, the combination with a 15 rigid jaw, of a jaw pivoted relatively to the rigid jaw to swing toward the latter through different angles for gripping different thicknesses of material, one of said jaws comprising a gripping member mounted to move 20 bodily lengthwise of said jaw into different angular relations to the other jaw in response to pressure upon the material to equalize the pressure between the inner and the outer portions of the gripping faces of 25 the jaws in different angular relations of the jaws.

5. In a gripper, a jaw, a coöperating jaw movable relatively to said first jaw into position to grip stocks of different thicknesses, 30 and a gripper plate associated with one of said jaws constructed and arranged to grip the stock with increasing force at the outer portions of the gripping faces of the jaws in response to strain tending to pull the stock 35 out of the gripper.

6. In a gripper, a jaw, a coöperating pivoted jaw having in its face adjacent to the first jaw a recess the bottom wall of which is concavely curved longitudinally of the jaw, 40 and a gripping plate seated in said recess and movable in the direction of the curvature of the recess to bite the upper material with increasing force at the outer portions of the gripping faces of the jaws in response 45 to strain tending to pull the upper material out of the gripper.

7. A gripper having, in combination, a pair of jaws mounted for relative movement into position to grip material between them, 50 one of said jaws having a recess in its inner face and a gripping member mounted in said recess for bodily adjustment angularly relatively to the other jaw in response to engagement with the material, and spring 55 means arranged to oppose yieldingly adjusting movement of said member by pressure directed toward said recess and to return the member to a normal position when the gripper releases its hold upon the material.

60 8. A gripper having, in combination, a pair of jaws mounted for relative movement into position to grip material between them, one of said jaws having a recess therein to provide a concavely curved bearing and a

gripping member mounted in said recess for 65 angular adjustment on said bearing relatively to the other jaw in response to engagement with the material, and a resilient plate arranged to press upon said member to determine a normal position of the member 70 on its bearing while permitting the adjusting movement of the member to take place against the tension of said plate.

9. A gripper having, in combination, a pair of jaws mounted for relative swinging 75 movement into position to grip material between them, one of said jaws having a recess in that face which is opposite to the other jaw to provide a bearing curved substantially about an axis extending laterally of 80 the gripper, and a gripping member mounted on said bearing for adjustment relatively to the other jaw about said axis in response to engagement with the material.

10. A gripper having, in combination, a pair of jaws mounted for relative movement into position to grip material between them, one of said jaws having a recess therein to provide a bearing concavely curved lengthwise of the gripper and a gripping member 90 mounted on said bearing for movement into different angular relations to the other jaw, the axis of curvature of said bearing being located substantially at that side of said member upon which the gripping face of the member is located to cause the outer edge portion of the member to bite the material with increasing force in response to relative pull between the gripper and the material 95 lengthwise of the gripper.

11. A gripper having, in combination, a pair of jaws mounted for relative swinging movement into position to grip material between them, one of said jaws having a recess therein to provide a bearing concavely curved about an axis substantially parallel to the axis of relative movement of the jaws and a gripping member mounted on said bearing for adjustment into different angular relations to the other jaw in response to engagement with the material, the axis of curvature of said bearing being located substantially at that side of said member upon which the gripping face of the member is located.

12. A gripper comprising a pair of jaws relatively movable to grip material between them, one of said jaws comprising a gripping member and a bearing for said member on which the member is movable bodily lengthwise of said jaw, said bearing being constructed to cause the member to be forced toward the other jaw in response to pull of the gripper upon the material in such direction as to increase the bite of the jaws upon that portion of the material which is engaged by the outer edge of said member.

13. A gripper comprising a pair of jaws

relatively movable to grip material between them and movable also to pull the material, one of said jaws being provided with a recess the bottom wall of which is inclined to the direction of the pull of the gripper and having a gripping member mounted in said

recess to be forced by said inclined wall toward the other jaw in response to the pull upon the material.

In testimony whereof I have signed my name to this specification.

CHARLES FAWCETT BENNION.
